TYING MACHINE

Benjamin H. Bunn, Chicago, Ill., assignor to B. H. Bunn Company, Chicago, Ill., a corporation of Illinois

Application December 26, 1941, Serial No. 424,388

16 Claims. (Cl. 100—31)

My invention relates to machines which wrap and knot twine about packages and the like. More especially it concerns a type of tying machine known in the art as a needle arm tying machine, that is, a tying machine in which the arm which lays or wraps the twine does not pass around the package as in the instance of a crank type wrapping arm, but instead has more of a reciprocating motion.

The needle arm tying machine exemplified by my Patent 2,274,526, issued February 24, 1942, normally positions a vertical terminal reach of twine extending upwardly from the table so that a package to be tied may be pushed against the reach to deflect it and thereby form a bight in the reach partially surrounding the package, the twine arm, which supports the upper end of the reach then descending, clearing the package, to complete the encirclement of the package, whereupon the two ends of the reach are secured together as by a knotting mechanism. The term "needle arm" derives from the analogy to the reciprocating vertical movement of a sewing machine needle.

An outstanding advantage of the needle arm type of tying machine—and an advantage which I seek to retain in my present invention—is that the movement of the package about to be tied into its twine reach deflecting position for the initial partial encirclement of the package, as above described, may be employed to push away from the wrapping zone the preceding package which has just been tied. This is possible in part because, with the needle arm machine, the twine need not be carried completely around the package by the twine arm as is the case with a crank type of twine arm, such as shown in my patents, Nos. 1,606,290 of November 9, 1926 and 1,994,453 of March 19, 1935.

The tying machine of my present invention is adapted to place single wraps of twine about packages, and securing the ends of the wraps together in rapid succession. The successive packages do not necessarily have to be of uniform height, width or length, but this tying machine of my present invention will accommodate successive packages of widely varying dimensions. Packages to be tied may include a wide field of types of varieties of boxes or cartons with or without paper wrappings, stacks of flat articles, such as envelopes or knock-down cardboard cartons, bundles of elongated articles, or wrapped or unwrapped rolls.

The tying machine of my invention is well adapted for the reception and immediate tying of

products of an automatic or semi-automatic machine as they are discharged therefrom. This usually necessitates a high-package-per-hour capacity of the tying machine to keep up with the production rate of the packages to be tied. The machine of my present invention is calculated to accommodate that production even though the tying machine operator is relatively unskilled.

Among the objects and features of my present tying machine are the following:

A more positive holding of the package to be tied during the wrapping and tying operations;

Easy, quick and simple adjustment of a package hold-down which permits the accommodation of packages of various heights;

Guarding the operator's fingers against injury by the hold-down and other mechanisms of the machine, without interfering with the movement of packages to and through the tying machine in rapid succession or even, if desired, in juxtaposed contact;

A safety release preventing injury to the package or to the machine in case a package or other obstruction is inadvertently positioned in the path of the needle arm when it moves down;

Operator fatigue reduction by light pressures on manually engaged control elements which are positioned for natural and easy engagement;

An easier operating clutch release for the machine which makes for a more accurate critical alignment of cam-operated parts; and

An improved path or orbit for the needle arm and of the mechanism for effecting the path.

The foregoing together with further objects, features and advantages of my invention are set forth in the following description and accompanying drawings of a specific embodiment thereof.

In the drawings, of which there are seven sheets:

Fig. 1 is a view in front elevation of a needle arm tying machine embodying the present invention, a portion of the front frame thereof being broken away, together with a portion of a cam and cam shaft, and a portion of a clutch hub portion being shown sectionally;

Fig. 2 is an enlarged fragmentary section on the offset planes of the broken line 2—2 of Fig. 1 with the needle arm in raised position, the solid lines indicating the position of the twine and package hold-down means prior to the insertion of a package for wrapping, and the dotted lines indicating the positions assumed by such parts after the insertion of a package;

Fig. 3 is a view similar to Fig. 2, showing the

package inserted and the needle arm in its lower-most position assumed in completing a wrap of twine about the package, the knotting mechanism being omitted for the purpose of simplicity;

Fig. 4 is a plan view of the machine illustrated in Figs. 1 to 3 inclusive;

Fig. 5 is an enlarged fragmentary section taken on the offset planes of the broken line 5—5 of Fig. 1;

Fig. 6 is a view similar to Fig. 5, showing the needle arm operating mechanism in downward position, and the needle arm in "broken," or safety released position, assumed after striking an improperly positioned package in the machine, the normal downward position of the needle arm being indicated in dotted lines;

Fig. 7 is an enlarged fragmentary section taken on the plane of the line 7—7 of Fig. 1 with the parts in their normal, or inter-cycle positions;

Fig. 8 is a fragmentary horizontal section taken on the plane of the line 8—8 of Fig. 2;

Fig. 9 is an enlarged fragmentary section taken on the plane of the line 9—9 of Fig. 5; and

Fig. 10 is an enlarged fragmentary section taken on the plane of the line 10—10 of Fig. 5.

The illustrated embodiment of my invention incorporates numerous features illustrated and described in detail in my Patent No. 1,606,290, issued November 9, 1926. For the purpose of simplifying the present specification, therefore, the reader is referred to said patent for an understanding of such features.

These features include the driving motor 21, a speed reducing drive connection between the motor and a clutch shaft 22, which in the disclosure of the patent is by means of a gear and pinion, but in the present illustrated structure is by means of V-pulleys 23 and 24, and a V-belt 25. A spring-pressed clutch 26 is provided for releasable driving engagement with the clutch shaft 22, and is provided with a clutch-operating yoked lever 27 and a clutch release link 28.

A pinion 29 is keyed to the clutch shaft 22 and is in constant meshed engagement with a mutilated gear 30. The mutilated gear and the mechanism operated thereby is somewhat different from that illustrated and described in the above-referred-to patent, No. 1,606,290, and will be described in detail later herein.

The knotting mechanism, indicated by the numeral 33, is similar to that of the patent, and includes a grooved, twine-pressing lever 34, for holding the twine against the bottom of a package during a knotting operation. There are provided also in the present embodiment, a pivoted and rotatable knotting beak 35, and a twine slide 36 to carry the reach of twine extending along the front face of a package being wrapped, to a point to the rear of the knotter beak so that the knotter beak can engage both reaches of the twine to perform the knotting operation. A spring-pressed, button-type, twine catcher 37 also is provided of the type described in my above-mentioned Patent No. 1,606,290.

Referring now to the drawings of the present case in detail, a frame 38 comprises front and rear frame members provided with cast iron frame plates 39 and 40, respectively, the front and rear frames being connected together as by tie rods 43 (see Fig. 1).

The frame is provided with a table-top member 44 of sheet metal having a portion 45 thereof extending forwardly therefrom and curved down-

ward slightly to facilitate placing a package 41 on the table as illustrated in Fig. 2 and sliding the package rearwardly to the dotted line position of Fig. 2, in which position the tying operation is performed. The extension 45 is supported by a bracket 46 secured at its lower end to the frame.

The table-top member 44 has an elongated notch 47 extending rearwardly from its forward edge, and is slotted transversely from the notch as at 48. The portion of the table-top rearwardly from said slit is bent downward slightly toward the slit, as illustrated in Figs. 2 and 3, to form a recess having a substantially vertical forward wall which is adapted to engage the lower front corner of a package inserted in the machine for wrapping, to prevent the package from being drawn forwardly by the tension on the twine during a tying operation.

The portion of the table-top to the right of the notch, see Fig. 4, preferably is materially shorter than that to the left of the notch, to permit a tying arm or needle arm 49 to clear the forward edge of this portion of the table to the right of the notch during the downward swing of the needle arm. A vertical side plate 50 extends upwardly from the right-hand edge of the table-top, as best illustrated in Figs. 1 and 4, and is mounted on angle brackets 53 secured to the frame.

Since each succeeding package may be used to push the preceding one rearwardly out of tying position, I illustrate a roller conveyor 51 mounted on the rear of the table, whereby the wrapped packages, as they are pushed off the table, are conveyed by this, or succeeding conveyors to a desired destination without the necessity of further manual operations.

Returning now to the clutch shaft 22 it will be noted that the pinion 29 is keyed to the clutch shaft 22 and is in meshed engagement with the mutilated gear 30. The left hand portion of the mutilated gear, as illustrated in Fig. 1, is continuously toothed throughout its periphery, and the pinion 29 is of a width to engage only this continuously toothed left hand portion of the mutilated gear.

The right hand portion of the mutilated gear has the teeth thereof removed throughout two portions of its periphery as at 54 and 55 in Figs. 1 and 7. Laterally adjacent to each of these untoothed portions of the mutilated gear is an arcuate flange 58 and 59, respectively, adapted to receive rollers 56 which are pivotally mounted upon laterally projecting studs on a needle arm drive gear 57 to prevent this needle arm drive gear from turning when the gear is over one of the mutilated or untoothed portions of the mutilated gear.

Four of the rollers 56 are provided on the needle arm drive gear as illustrated in Figs. 5, 6 and 7, these rollers being arranged in oppositely disposed pairs, and arranged to ride on the flanges 58 and 59 in sequence during the rotation of the mutilated gear during a wrapping operation. The needle arm drive gear 57 has two of its teeth cut away as at 60 and 61 on diametrically opposite sides thereof, and adjacent to each of these cut away portions in the direction of rotation of this gear are a pair of double toothed abutments 64 and 65 to receive the starting impact when this needle arm drive gear is engaged by the toothed portions on the mutilated side of the mutilated gear 30.

Each of the toothed portions of the mutilated gear has a number of teeth corresponding to the teeth of the half of the needle arm drive gear 57 which it is adapted to engage, so that during a complete rotation of the mutilated gear, which constitutes one complete operating cycle of the wrapping mechanism (since the cam block 68A which determines this cycle is mounted on the same shaft as the mutilated gear) there will be produced two half rotations of the needle arm drive gear 57, separated by an intermediate rest, or "dwell."

A chain drive sprocket 68 is secured to the needle arm drive gear 57 to rotate therewith, and is connected by means of a drive chain 67 to a similar driven sprocket 69 rotatably mounted on a stub shaft 71 in the frame. The driven sprocket 69 is secured to a needle arm support gear 69 to rotate therewith. The gear 69 is in meshed engagement with a second similar gear 70, mounted to rotate on a second stub shaft 74 mounted on the frame.

Each of the gears 69 and 70 has a stud, 75 and 76, respectively, mounted to project laterally therefrom. A needle arm support member 77 is pivoted on the stud 75, and has a socket 78 therein in which is secured the needle arm 49 which extends forwardly for a sufficient distance to clear the front edge of the right hand portion of the table-top 44, and there is bent at right angles to extend horizontally to the left as illustrated in Fig. 1, terminating in the same vertical fore and aft plane as the twine catcher 31. The free end of the needle arm is provided with a twine opening 79 through which the twine 80 is adapted to pass during the operation of the machine.

On the opposite side of the stud 75 from the needle arm 49 the support 77 is flat, as best illustrated in Figs. 1, 5 and 6, and is pivotally connected, by means of a stud 83 to a flat "break-away" portion 84. The rear end of the needle arm support 77 has an upwardly directed notch 85 therein, the edges of which are beveled and formed into a more or less circular seat as best illustrated in Figs. 6, 8 and 9, whereby the two parts of the needle arm support are adapted to be secured releasably together.

A cap screw 86 is threaded into the break-away portion 84 of the needle arm, as illustrated in Figs. 9 and 10, and is secured in position therein by means of a lock nut 87 threaded onto the projecting threaded end of the cap screw. A collar 88 is mounted for slidable movement on the stem of the cap screw 86, and a coil spring 89 is held in compression between the collar and the head of the cap screw. The lower face of the collar 88 is rounded in cross section to provide a cam action between the rounded lower face of this collar and the beveled edges of the notch 85, so that when the two portions of the needle arm support are swung into alignment, that is, the position illustrated in Fig. 5, the collar 88 will be cammed upwardly by the action of the bevelled edge of the notch and thereby will permit the collar to seat in the notch, where it is retained by the pressure of the compression spring 89.

A slotted opening 90 is provided in the break-away portion 84 of the needle arm support to receive the stud 76 carried by the gear 70, which stud is positioned diametrically opposite from the position of the stud 75 on the first gear 69. The slot 90 is of a length to permit free slidable move-

ment of the stud 76 therein during a complete cycle of rotation of the intermeshed gears 69 and 70.

During the first half of the rotation of the needle arm drive gear 57, induced by the action on it of the teeth of the initial fully toothed portion of the mutilated gear 30, the intermeshed gears 69 and 70 are rotated one half revolution each, and the outer end of the needle arm describes the first half of the flattened kidney shaped path indicated in dotted lines in Fig. 5, which constitutes its cycle of operation.

In other words, this first half of the cycle carries the needle arm from the solid line position illustrated in Fig. 2, through the dotted line path illustrated in Fig. 3 to the position of Fig. 3. In this latter position the arm dwells during the knotting and twine severing operations. These operations include the raising of the lowermost reach of twine against the bottom of the package by means of the grooved twine pressing lever 34, the moving of the strand of twine lying along the front face of the package rearwardly by means of the slide 36, to the right of the knotting beak, and the performing of the knotting operation as described in my above-mentioned patent. The completion of the knotting operation is followed by the severing of the twine, and the withdrawing of the twine from the twine catcher.

At the completion of the knotting and severing operations, the needle arm drive gear 57 is engaged by the second fully toothed portion of the mutilated gear 30, and is rotated through its second half-cycle. This restores the meshed gears 69 and 70 to their normal or initial positions illustrated in Fig. 5, and carries the twine arm through its second half-cycle indicated by the rear or left-hand half of the kidney-shaped dotted-line path indicated in Fig. 5.

It will be noted that while traversing the lower end of its cycle the horizontal portion of the needle arm is carried from the forward side of the twine catcher 37, below the twine catcher, and thence upwardly on the rear side of the twine catcher so as to hook the reach of twine around the twine catcher during this phase of the operation. This desirable feature of operation is accomplished by the pivotal arrangement of the twine arm support on the stud 75 combined with the action of the stud 76 in the slot 90.

During the initial quarter of the cycle of the gear 69, the stud 75 first carries the needle arm to the right from the position of Fig. 5 and bodily downward, and to the left and bodily downward during its second 90° of rotation. Simultaneously, and throughout the combined initial 180° of rotation of the gear 69, the stud 76 on the intermeshed gear 70 is traveling upward to its topmost position. This action tilts the needle arm clockwise about its pivotal mounting on the stud 75 and carries the forward end of the needle arm downwardly to the lowermost dotted-line position.

During the second half of the cycle, the mounting stud 75 is moved bodily rearwardly and upwardly by the action of the gear 69 during the first 90° thereof, and bodily forwardly and upwardly during the final 90° of this second half of the cycle. Simultaneously the downward movement of the stud in the slot 90 pivotally tilts the needle arm in a counterclockwise direction relatively to the pivotal stud 75, and thereby returns it to its starting position, shown in Fig. 5.

In case the needle arm should strike an ob-

struction during its downward travel, such as the improperly positioned package illustrated in Fig. 6, the additional stress imposed by this obstruction against the downward movement of the arm would overcome the resilient frictional engagement of the collar 88 in the beveled seat of the notch 85. This would free the needle arm support 77 for rotation about the stud 83 as a pivot, and thus would permit the arm to "break" to the position illustrated in Fig. 6. The mechanism would complete its cycle of operation with the arm in this broken or released condition. At the completion of such a cycle the needle arm and its extension 84 would again be snapped into their normal aligned positions, the package properly positioned, and a new wrapping cycle initiated.

Operating synchronously with the package wrapping and tying mechanism, is a package hold-down mechanism which is operated by means of a cam-track 92 in the side of the mutilated gear 30. While similar in some respects to the package hold-down arrangement of my patent, No. 1,606,290, this present hold-down mechanism has important distinguishing features which are described in the following paragraphs. The cam-track 92 is illustrated in Figs. 5 and 6, which, together with Figs. 1, 2, 3 and 4, illustrate the structure and features of the hold-down mechanism.

A cam-operated lever 93 is keyed to a shaft 94, which is journaled in the frame at one side of the mutilated gear 30, the outer end of the lever 93 being provided with a cam roller 95 adapted to ride in the cam-track 92. A second lever 96 also is keyed to the shaft 94, spaced axially from the first lever 93, and between these two spaced, but keyed together, levers, a third lever 97 is journaled for free pivotal movement on the shaft 94.

The third or pivoted lever 97 is provided with a laterally projecting stud 98 which passes through and beyond an opening in a vertically extending link 99, the outer projecting end of the stud 98 resting upon a projection 100 of the second lever in the normal, or at-rest, position of the machine, as illustrated in Figs. 1 and 5. A coil spring 103 interconnects the ends of the second and third levers 96 and 97 and is held in tension therebetween.

In the normal, or at-rest, position of the machine, the stud 98 is supported upon the arm 100 of the second lever 96, and the tension on the coil spring 103 is released or at a minimum due to the fact that the first lever 93 is in its maximum counterclockwise or upraised position, as illustrated in Fig. 5, thereby raising the vertical link 99 to its maximum elevation.

When the machine is operated, the first lever 93 initially is moved pivotally in a clockwise direction from the position of Fig. 5 by the action of the cam-track on the roller 95, moving this lever to the position illustrated in Fig. 6. Since the second or outer lever 96 also is keyed to the same shaft as the first lever 93, this second lever likewise is moved in a clockwise direction to the position illustrated in Fig. 6. This movement releases the stud 98 from its supported position on the projection 100 of the second lever 96, while at the same time it increases the tension on the coil spring 103, thereby drawing the third or intermediate lever 97 in a clockwise direction urging the link 99 downwardly.

The upper end of the link 99 is secured pivotally, as by a stud 104, to a coupling link 105

which has pivotal connection, as at 106 and 107, to two parallel arms 108 and 109. These two arms are pivoted at their right-hand ends, as illustrated in Fig. 1, to the frame as at 110 and 113, while the outer or free ends of these arms are connected pivotally, as by studs 114 and 115 (see Figs. 1 and 2) to a vertically disposed mounting strip 116. An angle bracket 117 is provided with a pair of slotted openings 118 and 119 therein, and is secured adjustably, as by means of cap screws 120 and 123, passing through these slotted openings, to the mounting strip 116. The lower end of the bracket 117 is bent at right angles to the upper portion thereof, and is secured, as by cap screws 124 and 125, to a package hold-down plate 126.

A safety guard assembly 127 is carried by the hold-down plate 126 and comprises an arm 128 of band steel, which is pivoted to the package hold-down plate at the rear end thereof, and extends forwardly to a point well ahead of the hold-down plate 126. A short arm 129 is pivoted coaxially with the long arm 128, on the opposite side of the hold-down plate, and is connected to the long arm by a tie strip 130 at the front end of the short arm 129. The tie strip acts to brace the long arm and limits its downward pivotal movement by engaging the top of the hold-down plate.

A guard plate 133 is pivotally mounted, as at 134, near the forward end of the arm 128, the lower edge of this guard plate being curved upwardly toward its forward end, as illustrated in Fig. 2, to provide a cam surface which will act to raise the safety guard member upwardly to the dotted-line position illustrated in Fig. 2, when a package is pushed rearwardly into position for tying, namely, from the solid-line to the dotted-line position of the package illustrated in Fig. 2.

A shorter auxiliary guard plate 135 is secured, as by a cross tie member 136, to the guard plate 133, and, together with the guard plate 133, prevents the operator from getting his fingers beneath the hold-down plate 126 during a package-wrapping operation of the machine.

An inertia type clutch release is provided for safe manual operation of the clutch release mechanism, and is mounted conveniently for operation by a flick of the right hand of the operator when withdrawing his right hand after positioning a package in the machine. This arrangement has a dual advantage in that (a) no lost motions are involved in the operation of the machine, and (b) it insures at the same time that the right arm of the operator will be withdrawn safely from the zone of operation of the horizontal portion of the needle arm 49 before initiating a wrapping and tying operation of the machine.

The clutch release comprises an operating lever 137 having a horizontally bent portion 138 adjacent the forward edge of the right-hand side of the table top 44. This lever is mounted in a socket 139 of a sleeve 140, which in turn is journaled on a stud 143 mounted on the frame. The clutch release lever 137, as illustrated, is provided with an upwardly curved offset 144 to clear the cam-shaft 145 during a down swing of the lever 137. The sleeve 140 is provided with an arm 146 to which is connected pivotally the slip link 28, which, in its normal position, is interposed between a cam-actuated lever 151, which is pivoted on a stud 152 on the frame, see Figs. 1, 2 and 8, and the clutch-actuating yoked lever 27.

The cam-actuated lever 151 has an offset portion which is adapted to engage a cam bar 147

on the side of the cam block and, when the clutch release lever is in normal or unoperated position, to force the slip link 28 outwardly against the clutch-actuating lever 27, thereby moving the clutch to released position. The slip link 28 may be withdrawn from its position between the lever 151 and the lever 27 upon counterclockwise movement of the sleeve 140 from the position illustrated in Fig. 2, to free the clutch control lever 27 for movement toward the cam block.

Release of the clutch control lever 27 permits the compression coil spring 31 in the clutch hub (see Fig. 2) to move the clutch to engaged position, and thereby causes a complete rotation of the cam block 65 in the direction of the arrow in Fig. 2. Upon completion of a rotation of the cam block, the cam bar 147 again will engage the cam-actuated lever 151 and force it away from the cam block. The slip link upon such completion of the rotation of the cam block will have returned to its normal position, illustrated in Fig. 8, under the combined action of a coil spring 148, held in tension between the socket 139 and the frame, and a counterweight 149 which is threaded on to a stud 150 secured to the sleeve. The slip link is forced by the action of the cam lever 151 toward the clutch-operating member 27, thereby moving the clutch to releasing position to complete a cycle of operation.

It will be noted by reference to Fig. 8 that a movement of the slip link 28 toward the right will have no interference from the clutch-operating member 27 or the cam lever 151 except the rolling friction of the roller carried by the member 27, and the sliding friction of the cam lever. With these parts lubricated properly such resistance is negligible, and is substantially less than that encountered with previously known arrangements. In the structure of my prior patent where the clutch release mechanism was operated by foot power, this objection was not serious, but in the present development it is an important consideration, since the release is intended for operation by a light flick of the operator's hand.

An important additional advantage of the present invention lies in the mounting of the cam lever 151 on the fixed pivot 152, since where, as in prior constructions, the cam lever is mounted to be bodily withdrawn from between the cam on the cam block and the clutch-operating member, there is a possibility that the cam lever will not always return to its same position after each operation.

The combined weights of the lever 137 and the counterweight 149 comprise a mass, the inertia of which, after a slight initial impact by the hand of an operator, carries the clutch release lever well downwardly to insure proper operation of the clutch upon each actuation of the lever. Adjustment of the weight on the threaded stud 150, together with an adjustable stop screw 161 mounted in a bracket 162 on the frame, permits the starting position and inertia of the lever to be adjusted to meet the requirements of an individual operator.

Even the most unskilled operator soon becomes very deft in inserting a package, holding it in proper position with the left hand positioned against the safety guard plate 133, and then withdrawing the right arm and simultaneously flicking the operating lever down to clutch-releasing position, thereby initiating the wrapping and tying cycle of the machine.

The machine may be adapted readily for the

wrapping of different sizes of packages by adjusting the package hold-down bracket 117 upwardly or downwardly with respect to the mounting strip 116. This is accomplished by loosening the two cap screws 119 and 120 which secure the bracket to the mounting strip, and, after such adjustment is completed, again tightening these cap screws.

A twine container 153 is mounted within the lower portion of the frame, as illustrated in Fig. 1, and is adapted to receive a supply of the twine 80. A twine guide opening is provided as in the motor support bracket 155 through which the twine is passed, and then is led through a spring-controlled twine tensioning device 156, which is similar generally to that disclosed in my above set forth patent.

From the twine tensioner the twine passes upwardly and through a guide opening in an extension 157 of the side plate supporting bracket 53. From this point the twine is led through the opening 78 in the outer end of the needle arm, from which point it passes to the twine catcher 37, where it is held in position by the spring action of the twine catcher.

The general operation of the machine is as follows: In the initial or normal condition of the machine, the clutch is disengaged, the arm 49 is in the elevated position shown in Figs. 2, 5 and 7. The terminal length 80 of the twine extends from the twine catcher 37 to the outer end of the needle arm 49. A package 41 is inserted from the full line to the dotted line position in Fig. 2. This raises the guards 133 and 135 to their dot and dash position in Fig. 2. The terminal length of the twine 80 moves from this full line position to its dot and dash line position in Fig. 2, the terminal length 80 being increased from the supply. The hold-down plate 126 is above the package 41, the gear 30 being in the position of Fig. 5. One pair of the rollers 56 rides upon the flange 58 as shown in Fig. 7. The operator having located the package as shown in dot and dash lines in Fig. 2 then actuates the clutch control lever 137 so that the gear 30 is now driven. During the first quarter revolution of the gear 30 the arm lever 93 is moved down so that the hold-down plate is brought into engagement with the top of the package 41. After the package is thus engaged the rollers 56 have cleared the flange 58 and the gears 69 and 70 are driven half a revolution. The arm 49 is thereby moved downwardly into the position shown in Fig. 3. This completes the wrap of the twine around the package. The hold-down plate and the arm 49 remain stationary while the twine is knotted. After the knotting of the twine the lever 93 is moved upwardly again by the cam track 92, thus elevating the hold-down plate away from the package, leaving it free for removal. Thereafter, the other pair of wheels 56 have ridden over the flange 59 and clear the flange so that the gears 69 and 70 are driven another half revolution. This brings the new terminal end of the twine, which is held by the twine catcher 37 into original position shown in Fig. 2. After this half revolution of the gears 69 and 70, the first mentioned pair of wheels 56 again engage the flange 58. When the gear 30 has made one revolution the clutch is automatically disengaged.

My present machine is particularly well adapted to the rapid wrapping of standard size packages, where it is desired to have but a single wrap of twine around the package. The right-

through, side-to-side contact of the packages permitted by the operating features of my machine recommend it particularly to straight-line manufacturing processes, such for instance as the receiving, wrapping and tying of the products of automatic or semi-automatic machines.

While I have illustrated a preferred embodiment of my invention, many modifications may be made without departing from the spirit of the invention, and I do not wish to be limited to the precise details of construction set forth, but desire to avail myself of all changes within the scope of the appended claims.

I claim:

1. In a package tying machine, a needle arm having a twine feeding opening in an end thereof, needle arm operating means comprising a rotatable member pivotally supporting the needle arm eccentrically to the axis of rotation of the rotatable member to move the pivot of the needle arm bodily in a circular path on rotation of the rotatable member, and tilting means connected to the needle arm to tilt the twine feeding end of the needle arm in its direction of bodily movement by the rotatable member on each of two opposite sides of a predetermined diameter of the path of rotation of the rotatable member.

2. In a package tying machine having a frame, and a twine catcher mounted on the frame; a rotatable member mounted on the frame, a needle arm connected to the rotatable member eccentrically to its axis of pivotal movement, the needle arm having a twine feeding opening in an end thereof, a second rotatable member connected for rotation synchronously with first said rotatable member, means in eccentric relation to said second rotatable member pivotally connecting the second rotatable member to the needle arm, the connections between the needle arm being co-related so that when one connection is down, the other connection is up and vice versa to produce a combined rotating and tilting movement of the twine feeding end of the needle arm to carry said end of the needle arm around the twine catcher.

3. In a package tying machine having a frame, a twine catcher on the frame, and a package support on the frame; a pair of intermeshed similar gears pivotally mounted on the machine, pivotal mounting means eccentrically carried by each gear, a needle arm pivoted on the pivotal mounting means on one gear for bodily movement in a circular path, an end of the needle arm having a twine feeding opening therein, and means interconnecting the other end of the needle arm and the pivotal mounting means of the second gear to tilt the needle arm about its pivotal axis on each of two sides of a diameter of the gear pivotally supporting the needle arm substantially perpendicularly to a line interconnecting the axes of the intermeshed gears, to move the twine feeding end of the needle arm in a flattened vertical orbit adjacent an end of the package support, for passing the twine feeding end of the needle arm around the twine catcher at one end of the orbit.

4. In a package tying machine, a frame, a twine catcher on the frame, a package support on the frame, a pair of intermeshed gears mounted adjacent to the package support, pivotal mounting means on one gear eccentric to its axis of rotation, second pivotal mounting means on the other gear the two pivotal mounting means and their intermeshing gears being so arranged that the mounting means are substantially al-

ways on opposite sides of a plane passing through the axes of the gears, a needle arm pivotally mounted on the pivotal mounting means of the first gear and having a slideable connection with that of the second gear, the needle arm having a twine feeding opening in the end thereof remote from said pivotal mounting, the rotation of the gears moving the twine feeding end of the needle arm in a flattened orbit adjacent an end of the package support, for passing the twine feeding end of the needle arm around the twine catcher at one end of the orbit.

5. In a package tying machine, a frame, a twine catcher supported on the frame, a package support mounted on the frame, a pivotal mounting member mounted for forward and backward cyclical movement relatively to the frame, a needle arm pivotally mounted on the pivotal mounting member to be carried backward and forward therewith, the needle arm having a twine feeding opening in an end thereof, and vertical reciprocating means operated synchronously with the pivotal mounting member and operatively connected to the needle arm to move the twine feeding end of the needle arm in a flattened elongated orbit to pass the twine feeding end of the needle arm around the twine catcher.

6. A package tying machine comprising, in combination with a frame, a twine catcher supported thereon, a package support carried by the frame, and a needle arm having a twine feeding opening in an end thereof to support a reach of twine with a bight thereof about a package on the package-supporting means, the opposite end of the reach of twine being secured in the twine catcher; a pair of intermeshed gears operatively connected to the needle arm, one of the gears comprising a pivotal support for the needle arm bodily to move the needle arm in a circular path on a rotation of said gears, and the other of the gears having a slideable connection with the other end of the needle arm, to move the first said end of the needle arm having the twine feeding opening therein in an elongated substantially vertical path adjacent the package support, to carry the twine feeding end of the needle arm around the twine catcher.

7. In a package tying machine, a frame, a twine catcher supported on the frame, a package support mounted on the frame, a pivotal mounting member mounted for forward and backward cyclical movement relatively to the frame, a needle arm actuating member mounted for vertical cyclical movement synchronously with the pivotal mounting member, a needle arm having a twine feeding opening in an end thereof pivotally mounted on the pivotal mounting member, a releasable extension on the needle arm connected to the needle arm with sufficient strength to withstand ordinary stresses in the operation of the tying machine, but releasable from the needle arm on the imposition of a stress thereon materially in excess of normal, the extension being connected to the needle arm actuating member to move, in conjunction with the pivotal mounting member, the twine feeding end of the needle arm in a flattened elongated orbit, the twine feeding end of the needle arm being adapted to pass around the twine catcher.

8. A package tying machine comprising a frame, a twine catcher supported on the frame, a package support mounted on the frame, a pivotal support rotatably mounted on the frame, a needle arm pivotally mounted on the pivotal sup-

port, the needle arm having a twine feeding opening in an end thereof, a slotted extension member connected to the needle arm at the opposite end from the twine feeding opening, a spring catch mounted to retain the arm and the extension in predetermined relative positions, and an operating member slidably mounted in the slot of the extension member, said operating member operating oppositely to the pivoted needle arm support to tilt the twine feeding end of the needle arm toward the direction of movement of the pivot to pass the twine feeding end of the needle arm around the twine catcher.

9. In a package tying machine comprising a frame, a twine catcher supported on the frame, a package support mounted on the frame, a needle arm, means for moving the needle arm down and up in an orbital path adjacent the package support; a combined package hold-down and safety guard comprising a hold-down member mounted to overlie a package positioned on the package support, means mounted to move the hold-down member down and up ahead of the down and up movements of the needle arm, a safety guard member pivoted to the hold-down member normally to extend materially below the hold-down member and laterally adjacent thereto to contact by gravity the top of a package on the package support, and to remain by gravity in contact with the package during a reciprocating hold-down and release movement of the hold-down member.

10. In a package tying machine comprising a frame, a twine catcher supported on the frame, a package supported mounted on the frame, a needle arm, means for moving the needle arm down and up in an orbital path adjacent the package support; a combined package hold-down and safety guard comprising a hold-down member operatively connected to move down and up ahead of the down and up movement of the needle arm, a safety guard support arm pivotally connected to the hold-down member, and a guard plate pivotally connected to the support arm and positioned alongside the hold-down member to extend below the hold-down member, stop means mounted to limit the downward movement of the guard plate under gravity, the lower edge of the guard plate being cam shaped to cam the guard plate upward over a package inserted into tying position on the package support, the hold-down member being moved vertically into hold-down relation to the package before an operation of the needle arm.

11. In a package tying machine having a frame, a twine catcher supported on the frame, a package support mounted on the frame, a needle arm, means for moving the needle arm down and up in an orbital path adjacent the package support; a combined package hold-down and safety guard comprising a hold-down member operatively connected to move down and up before the down and up movements of the needle arm, a safety guard support arm pivotally connected to the hold-down member, a guard plate pivotally connected to the support arm and positioned alongside the hold-down member to extend below the hold-down member, a cross tie member secured to the first guard plate and extending across the upper side of the hold-down member to limit the downward movement of the guard plate, and a second guard plate mounted on the end of the cross tie member on the opposite side of the hold-down member from the first guard plate.

12. In a package tying machine comprising a frame, a twine catch supported on the frame, a package support mounted on the frame, a needle arm, means for moving the needle arm down and up in an orbital path adjacent the package support; a combined package hold-down and safety guard comprising a hold-down member operatively connected to move down and up before the down and up movements of the needle arm, a relatively long safety guard support arm pivotally connected adjacent one end thereof to the hold-down member and a guard plate pivotally connected adjacent the other end of the support arm, and positioned alongside the hold-down member normally to extend below the hold-down member, a cross tie member secured to the first guard plate and extending across the upper side of the hold-down member to limit the downward movement of the guard plate, a second guard plate mounted on the end of the cross tie member on the opposite side of the hold-down member from the first guard plate, a relatively short arm opposite to the long guard plate support arm and mounted co-axially therewith, and a cross tie connecting the end of the short arm to an intermediate portion of the long arm.

13. In a package tying machine comprising a frame, a twine catcher supported on the frame, a package support mounted on the frame, a needle arm, means for moving the needle arm down and up in an orbital path adjacent the package support; a package hold-down, a cam mounted to move the hold-down down and up before the down and up movements of the needle arm, a lever operatively connected to the cam, a second lever keyed to the first, a third lever pivoted adjacent the second lever, a pin projecting laterally from the third lever, a link pivotally connected to the pin and extending upwardly therefrom, said package hold-down being operatively connected to the link, a cam operated member mounted beneath the pin normally holding the pin and its connected link upwardly, a spring interconnecting the cam actuated lever and the pivoted lever, said spring connected cam actuated lever being moved by an operation of the cam to exert spring action on the pivoted lever to urge the pivoted lever and its connected link downward thereby to move the package hold-down toward a package holding position, the pin support being removed on an actuation of the cam actuated lever.

14. A package tying machine comprising a frame, a twine catcher supported on the frame, a package support mounted on the frame, a needle arm, means for moving said needle arm down and up in an orbital path adjacent the package support; and a package hold-down comprising a hold-down member, a pair of parallel arms pivoted at one end of each thereof to said hold-down member and at their other ends to the frame, a link pivotally connected to the parallel arms and extending downwardly therefrom, a cam mounted below the parallel arms and operatively connected to said link and the needle arm, lever pivotally mounted on the frame and having resilient operative connection to the cam, means normally supporting the link and parallel arms and hold-down plate in upward position, the supporting means being carried out of supporting position on an operative movement of the cam to increase the tension on the resilient connection to the cam, thereby urging the pivoted lever, the link, the parallel arms, and the hold-down member downward into pack-

age holding position, said cam being arranged to move the hold-down member downwardly before the downward movement of the needle arm.

15. The combination of claim 2 wherein the needle arm is made in two parts releasably interconnected to constitute a rigid arm providing a safety break in the arm, one of said connections being made to one of said parts and the other of said connections to the other of said parts and said safety break being placed intermediate said connections.

16. A tying machine having a needle arm, means for moving said arm bodily and laterally in opposite directions, independent means for tilting said arm upwardly and downwardly in

synchronized relation with its lateral movements whereby one end of said needle arm describes an elongated vertical figure, said needle arm comprising two parts, and releasable means normally holding the two parts rigidly interconnected, the holding means being of a strength to be released by the imposition thereon of stress materially in excess of normal operative stresses to break the needle arm and prevent damage from excess stresses, said means for effecting lateral movement and the tilting means being connected to separate parts of said needle arm, the holding means being located therebetween.

BENJAMIN H. BUNN.
